(57) **CLAIM**

The ornamental design for flange for water pump, as shown and described.

DESCRIPTION

FIG. 1 is a front elevational view of a flange for water pump showing my new design;

FIG. 2 is a top plan view thereof;

FIG. 3 is a bottom plan view thereof;

FIG. 4 is a left side elevational view thereof;

FIG. 5 is a rear elevational view thereof;

FIG. 6 is a front perspective view thereof;

FIG. 7 is a reference front elevational view;

FIG. 8 is a cross sectional view along line A-A as shown in FIG. 7;

FIG. 9 is a reference top plan view;

FIG. 10 is a cross sectional view along line B-B as shown in FIG. 9;

FIG. 11 is a reference perspective view illustrating a use state thereof; and,

FIG. 12 is a reference perspective view illustrating a use state thereof.

In the drawings, the dashed broken lines show portions of the flange for water pump form no part of the claimed design. The dashed broken lines define the bounds of the claimed design and form no part thereof.
